BRASSIERE

Edward E. Astor, Saddlebrook, N.J., assignor to International Latex Corporation, Dover, Del., a corporation of Delaware

Filed Jan. 5, 1961, Ser. No. 63,446

Term of patent 14 years

(Cl. D20—4)

FIG. 1.

FIG. 2.

FIGURE 1 is a plan view of a brassiere showing my new design.

FIGURE 2 is an enlarged view of a fragmentary portion of the brassiere pocket of FIGURE 1.

The characteristic feature of my design resides in the combination on the brassiere disclosed of the specific panel between the pockets which panel extends below the inner halves of each pocket, the panel and the upper pocket halves being stitched with five-pointed embroidered clusters having curved ends, in association with the horizontal median and the bottom half of the vertical median of each pocket having a wide ribbon band with diamond stitching thereon presenting an appearance of a decorative Gothic T, all as shown.

I claim:

The ornamental design for a brassiere, substantially as shown and described.
